UNITED STATES PATENT OFFICE

HENRY ELTON PEASE, OF CHICAGO, ILLINOIS, ASSIGNOR TO STANDARD SHOW CARD SERVICE, INC., OF CHICAGO, ILLINOIS, A CORPORATION OF ILLINOIS

INTERCHANGEABLE CARD SIGN

Application filed February 27, 1929. Serial No. 343,069.

This invention relates to interchangeable card signs of a type adapted for merchandising use.

The general object of the invention is the provision of a simple and economical interchangeable card sign which may be used by merchants to advertise a wide variety of commodities and afford a varied selection of price markings and informative or advertising matter for display in such association with the names of the various commodities that the composite sign will have the appearance of a unitary show card. The purpose is to provide the dealer with an assortment of display cards so related that they may be arranged to afford a wide variety of displays, each of which will have the appearance of a specially prepared show card.

Since the various cards are intended for repeated use, the invention has as an object also the provision of a display device of the sort specified which will be effective to protect and conceal portions of the cards, such as the edges, which are likely to become worn with repeated use and handling.

Other objects of the invention will be pointed out or indicated hereinafter or will become apparent upon an understanding of the invention or its employment in use.

In the accompanying drawing forming part of this specification is shown an embodiment of the invention, it being understood the same is presented by way of example of one of the various forms which the invention may take.

In the drawing

Fig. 1 is a front elevation of the sign as assembled for display;

Fig. 2 is a longitudinal section of the same;

Fig. 3 is a view of one side of one of the commodity cards;

Fig. 4 is a view of one side of the price cards; and

Fig. 5 is a view of one side of the supplementary cards.

The nature of the invention and of its employment will be most quickly ascertained by consideration of the example shown in the drawing. I provide a card holder in the nature of a frame 10 having grooved side and

bottom members and a slotted top member. The width of these grooves and slots is such as to accommodate three cards 11, 12 and 14 and maintain them in close face contact with one another. The card 11 I will designate, 55 for purposes of distinction, the commodity card, the card 12 the supplementary card and the card 14 the price card. The dealer will be supplied with such number of the commodity cards, all adapted to fit the frame, as 60 to meet his requirements. Each side of each commodity card is apportioned by transverse stripes or bands 15 into three panels, the intermediate panel preferably being of a different color from the upper and lower panels, 65 and the stripes or bands being of a color contrasting with both. The height and arrangement of these panels is such that the commodity panels are of equal height and the intermediate panel is of considerably less height 70 and extends for equal distances on opposite sides of the transverse median line of the card. On each of the four commodity panels thus afforded by each card is suitably lettered the name of some commodity handled by the 75 dealer, the top of the lettering in each instance being toward the proximate end of the card. In the half of each of the intermediate panels is adjacent the respective commodity panels is displayed an informative or advertising 80 legend appropriate to or relating to the commodity named in the adjacent commodity panel. Thus each commodity card bears the names of four commodities with appurtenant informative or advertising matter.

Each of the price cards 14 is approximately one-half the height of the commodity cards, and on each side bears a price designation. Also, along its upper edge on each side, the price card is finished with a stripe or band 16 90 corresponding in width and color to the stripes or bands 15 of the commodity card. Accordingly, when one of the commodity cards is placed in the frame and one of the price cards is inserted in the frame in front of it, and both seated in the slot of the bottom frame member, the assembled sign will display in its upper portion the commodity name which appears in the upper part of the commodity card, and below this the upper 95 100

half of the intermediate and differently colored panel of the commodity card with the legend which appears thereon, and below this the price designation which appears on the price card, the intermediate differently colored panel being lined at the top by the stripe 15 and at the bottom by the stripe 16 of the price card. These stripes being of similar color, and the strip 16 following the margin of the price card, the assembled sign will have the appearance of an integral card with a contrasting panel or middle, and all the markings displayed, viz, the name of the commodity, the informative 15 or advertising legend, and the price designation, all being appropriately related. For example, if the dealer wishes to advertise cod liver oil at its regular price, say at one dollar, he will assemble the commodity card 20 with the cod liver oil legend at the top and place the one dollar price card in front of it at the bottom. This will leave exposed the advertising legend associated with the cod liver oil name, so that, in the example illustrated, the display will read Cod liver oil 25 prevents colds "\$1.00". On another occasion, as if he should desire to advertise cod liver oil at a reduced price, he may employ one of the supplementary cards 12. These cards 30 are of a height not less than the combined height of a commodity panel and the intermediate panel of the commodity card, and are of a color different from that of the commodity panel, preferably the same color as that of 35 the intermediate panel. Along the upper and lower margins on each side, the supplementary card is finished with a stripe or band 17, preferably corresponding in width and color to the stripes 15 and 16. Also at both 40 ends on each side, the supplementary card is provided with legends which may be used in conjunction with various commodities, the top of the lettering in each instance being toward the proximate edge of the card. Accordingly, if the dealer wishes to substitute 45 in his display some legend for that associated with the particular commodity on the commodity card, he will insert the selected supplementary card into the frame between the 50 commodity card and price card, with the selected expression at the top of the supplementary card; with the result that in the assembled sign the legend on the supplementary card will appear in the place of that in the 55 intermediate panel of the commodity card, and the assembled sign will still have the appearance of an integral card with the name of the commodity in the upper portion, the price in the lower portion, with intermediate 60 panel of a different color displaying an appropriate legend. Thus, if the dealer wishes to advertise cod liver oil at a reduced price, he may employ the supplementary card as above described to show a legend such as This 65 week only or regular \$1.00 size below the

commodity name and over the reduced price designation shown on the price card, so that the display will read, for example, Cod liver oil regular \$1.00 size 93¢.

In this fashion the dealer is afforded a great 70 variety of displays adapted to the advertising of his various commodities at various prices and with a wide selection of special information, each selective display having the appearance of an integral display card such 75 as might have been prepared specially for the occasion, yet the great variety of possible permutations and combinations requiring relatively few cards.

Where show cards are employed in windows, on counters, or suspended against shelves or the like, they are likely to have their edges bruised or nicked or otherwise worn in handling and by being struck by articles. In the present construction the cards assembled 80 in the sign are effectively protected at the edges by the frame, so that they are not subject to these disfigurements and hence may be used repeatedly without showing evidences of 85 wear.

As an additional feature a specially formed card 18 may be provided for display above the frame, the same being provided with a portion 18^a adapted to fit in the frame slots 90 behind the upper end of the commodity card, and a laterally extending portion adapted to 95 rest on the top of the frame, whereby the display portion is maintained in desired association with the rest of the sign.

What I claim is:

1. An interchangeable card sign comprising, in combination, a frame having its members slotted to receive a plurality of cards and maintain them in contact face to face, a commodity card subdivided by transverse stripes into commodity panels of equal height at its ends and an intermediate panel, a price card of approximately one-half the height of the commodity card and bearing different price indicia on its opposite sides and provided along its upper margin with a stripe corresponding to those on the commodity card, and a supplementary card provided along its upper and lower margins with stripes corresponding to those on the other cards and with legends adjacent to said stripes, said supplementary card being of a height not less than the aggregate height of the intermediate panel and a commodity panel of the commodity card, and all of the cards being of suitable width to fit into the grooved frame. 105

2. An interchangeable card sign as specified in claim 1 and wherein the supplementary card and the intermediate panel of the commodity card are of a color different from 110 that of the body of the other cards and the stripes are of a color contrasting with the body colors of the other cards.

3. An interchangeable card sign comprising a commodity card subdivided into an in- 115

termediate panel and end panels, the latter of equal length, each commodity panel bearing a commodity legend, the intermediate panel bearing respective legends in association with the respective commodity panels, a 5 supplementary card of a height corresponding to the aggregate height of the intermediate panel and a commodity panel and bearing legends adjacent its top and bottom edges, a price card bearing a price legend and of a height approximately one-half that 10 of the commodity card, the intermediate panel being delineated at top and bottom by transverse stripes and the top margin of the 15 price card and the top and bottom margins of the supplementary card being edged with corresponding stripes, and a support for holding the cards face to face in assembled relationship to display legends thereon one 20 above another.

4. An interchangeable card sign as specified in claim 1, and including an additional demountable card having a portion adapted to fit in the frame grooves behind the upper 25 portion of the commodity card and portions extending laterally therefrom adapted to rest on the top of the frame, to sustain said additional card in approximately the same plane as the other cards.

30 In testimony whereof I have hereunto subscribed my name.

H. ELTON PEASE.
